UNITED STATES PATENT OFFICE

OWEN H. SPENCER, OF INDIANAPOLIS, INDIANA

ENGINE PORT CONSTRUCTION

Application filed May 3, 1929. Serial No. 369,273.

This invention relates to internal combustion engines and the prime feature of the invention is the provision of means for more expeditiously clearing the cylinders of the motor of the exploded gases, whereby the new charge of gas will more readily enter the cylinders and without taking up any appreciable quantity of the exploded gas. To this end the exhaust ports are so arranged that certain ones thereof will overlap the intake ports so that the exhaust ports will extend more than one half the circumference of the cylinders, while the intake ports will be limited to substantially one half the circumference of the cylinders.

Other objects and advantages will be hereinafter more fully set forth and pointed out in the accompanying specification.

In the accompanying drawings which are made a part of this application,

Figure 1 is a vertical central sectional view through an internal combustion engine, with the piston shown in its extreme inward position.

Figure 2 is a sectional view thereof as seen on line 2—2 Fig. 1, and,

Figure 3 is a similar view as seen on line 3—3, Figure 1.

Referring to the drawings, in which similar reference characters designate corresponding parts throughout the several views, the numeral 1 indicates the cylinder of an internal combustion engine, in which is reciprocatingly mounted a piston 2, of the conventional form, said piston being operated within the cylinder by means of a crank shaft 3.

The wall of the cylinder 1 is provided in its lower portion with one or a plurality of exhaust ports 4, which extend more than one half the circumference of the cylinder, thereby providing sufficient exhaust opening through which the exploded heated gases may more quickly escape from the cylinder, than is possible with the present construction of cylinders.

The lower portion of the cylinder 1 is also provided with inlet ports 5, which also extend circumferentially of the cylinder and approximately one half the diameter of the

cylinder, and as the exhaust ports extend more than one half the diameter of the cylinder, that portion of the exhaust ports 4, projecting beyond the circumferential center of the cylinder, lie in a plane above the inlet ports 5 being separated therefrom by a wall 6.

The top edges of all the exhaust ports are preferably in line with each other so that they will all be uncovered simultaneously on the downward stroke of the piston 2, thus permitting the exhaust gases to enter all the exhaust ports substantially at the same time, and due to the multiplicity of the exhaust ports, the gas will rapidly leave the cylinder.

On the continued downward stroke of the piston 2, the inlet ports 5 will be uncovered, thus admitting fresh gaseous charge, the top end of the piston having a baffle 7 thereon, so arranged that the incoming charge of gas will be directed upwardly in the cylinder and be thus prevented from passing directly to the exhaust ports 4.

By providing the extended exhaust area, practically all the heated exhaust material will escape from the cylinder after each explosion, without delay, thus not only giving immediate room for the new charge, but also aiding in keeping the temperature of the cylinder at a comparatively low degree. By this arrangement the fumes from the explosive fumes are eliminated from the engine before any residue deposits collect within same such as carbon.

It will also be seen that the cylinder, the same as is commonly used, with the exception of the passage 8 into which the exhaust passes from the cylinder, such passage being somewhat enlarged to cooperate with the increased number of exhaust ports used.

What I claim is:

In an internal combustion engine, a cylinder, exhaust ports through the wall of said cylinder encircling substantially one half the circumference of said cylinder, additional exhaust ports around a portion of the remainder of the circumference of said cylinder and of a height less than the height of the first exhaust ports, an escape passage common to all of said exhaust ports, intake ports independent of the exhaust ports also

encircling substantially one half the circumference of the cylinder and underlying the shorter exhaust ports and at that side of the cylinder opposite said escape passage, and
5 solid walls entirely and permanently separating the intake ports from the exhaust ports, whereby the contents of the intake ports must pass into the cylinder before entering or contacting with any of the exhaust ports.

10 In testimony whereof, I have hereunto set my hand on this the 2nd day of May, 1929,
A. D.

OWEN H. SPENCER.
